STOMA RECEIVER OF SIMPLIFIED CONSTRUCTION FOR USE WITH A DISPOSABLE BAG

Murle Perry, Minneapolis, Minn.

Application September 10, 1951, Serial No. 245,821

4 Claims. (Cl. 128—283)

1

This invention relates generally to a stoma receiver and particularly to a greatly simplified assembly for converting a thin disposable bag into an efficient colostomy appliance.

It is an object of my present invention to provide an extremely simple stoma receiver particularly adapted for easy manufacture and of relatively inexpensive construction.

More specifically, it is an object to provide a stoma receiver assembly consisting in a highly flexible disposable bag structure having a pair of concentrically disposed annular clamping rings adapted to quickly and easily receive a portion of the rear layer of the bag therebetween in sealed, tightly clamped relation and having attachment means for mounting the outer ring onto the body of a wearer while positively locking said rings in clamping position.

These and other objects and advantages of my invention will more fully appear from the following description made in connection with the accompanying drawings wherein like reference characters refer to the same or similar parts throughout the several views and in which:

Fig. 1 is a perspective view showing a complete appliance embodying my invention in operative position on the body of a wearer;

Fig. 2 is a transverse vertical sectional view taken substantially through the center of the structure shown in Fig. 1;

Fig. 3 is a transverse horizontal sectional view taken substantially through the center of the stoma receiving aperture of the apparatus shown in Fig. 2; and

Fig. 4 is a semi-exploded view showing the individual members of my appliance in separate perspective illustrations.

As illustrated in the accompanying drawings, I provide an extremely simple and inexpensive colostomy appliance having a bag 8 made from any suitable thin, highly pliable waterproof material such as vinyl or polyethylene plastic sheet material. The upper end of the bag 8 is sealed, as indicated at 8a of Fig. 2.

An outer annular retaining and mounting ring, shown in perspective in Fig. 4 and designated by the numeral 9, is provided and has a pair of pivotally mounted attachment hooks 10 each with a hook 10a on one end thereof and an inwardly extending locking cam 10b on the other end thereof. An aperture 9a is centrally formed within ring 9 and has an annular clamping and sealing groove 9b which forms an annular shoulder 9c on the outer portion thereof. The inner surface of said ring 9 is smooth and is adapted to be disposed adjacent a body engaging absorbent pad 11, as shown in Figs. 1 and 2.

An annular clamping insert 12 having an external peripheral groove 12a forming a clamping shoulder 12b is also provided and is adapted to be

2

received within the central aperture of ring 9 with the shoulder 12b engaged against the shoulder 9c, as best shown in Figs. 2 and 3. The hooks 10 are swung into retracted position, as shown in Fig. 4, to permit clearance for insertion of the insert 12 therein.

To assemble my colostomy appliance, the inner layer 8b of bag 8 may be provided with a round cut out aperture 8c, as shown in Fig. 4, and this aperture is slightly larger than the inner aperture of insert 12, as best shown in Figs. 2 and 3. The inner aperture of insert 12 is smoothly contoured and rounded to prevent irritation to the stoma when engaged thereagainst during movement of the wearer. The insert 12 is slipped into the interior of the bag 8 and is positioned on the inside of the inner layer 8b with the smoothly contoured aperture substantially aligned with the aperture 8c. The shoulder 12b of the insert 12 is of course facing inwardly, as best shown in Figs. 2 and 3. The ring 9 with the shoulder 9c facing outwardly is then mounted over the insert 12 on the outside of the inner bag layer with the inner periphery of the aperture 9a in closely surrounding relation to the outer periphery of the insert 12 with the shoulders 12b and 9c tightly clamped together with the thin sheet material of the rear bag layer interposed in sealed relation therebetween. The camming 15 hooks 10 are then swung into insert locking position, as shown by the full lines of Fig. 4, and also shown in Fig. 3. The camming ends 10b are smoothly contoured to prevent injury or tearing of the engaged portion of the bag and the hooks 10a are of course disposed on the outside of 20 mounting and retaining ring 9, as best shown in Fig. 3. In Fig. 4, the inner layer 8b of the bag is viewed to show the inner surface thereof and the insert 12 is shown with the shoulder 12b disposed in its normal position in inwardly facing relation and of course is inserted behind the inner bag layer 8b in the position illustrated. However, in order to more clearly illustrate the 25 peripheral groove 9b and shoulder 9c, the attachment and retaining ring 9 is shown in inverted position with the outer surface presented for view. In order to assemble my appliance, the ring 9 must be turned around to face the outer surface containing the hooks 10 and adjacent the shoulder 9c toward the outside of the structure.

Any suitable means may be used for closing the lower end of the bag, such as a flexible, cylindrical clamping roll 13 and resilient clip 14, as best shown in Fig. 1. Also, the two belts 15 and 16 may be attached in any conventional manner at their ends to the respective hooks 10 as by the attachment elements 17.

It should be noted that the insert ring 12 is substantially thicker than the mounting and retaining ring 9 and that the shoulder 12b is dis-

posed substantially adjacent the outer surface of said ring 12, that is the surface disposed within the bag 8, thereby positioning the inner smoothly contoured surface in protruding relation relative to the ring 9, as shown in Figs. 2 and 3. When the two rings are in assembled position, this protruding of the insert ring 12 toward the body of the wearer forms a pressure boss surrounding the stoma and forms a relatively tight seal against the pad 11 to securely hold the same around the stoma and permit limited tilting of the ring assembly unit while maintaining a sealing pressure around the stoma. The insert ring 12, due to the resiliency of the plastic material of the bag 8, may be inserted through the aperture 16 and positioned inside of the bag adjacent said aperture and the outer mounting and retaining ring clamped thereagainst in the manner previously described.

It will be seen that I have provided an extremely simple colostomy appliance particularly adapted for inexpensive manufacture and sale and providing only a minimum of separate parts while producing highly efficient results. The simplicity of design of my invention disclosed herein is an extremely important part of the inventive concept thereof since only two separable cooperating clamping members are provided to securely attach and seal the upper portion of a bag of the inexpensive disposable or semi-disposable type in operative position surrounding the stoma of the wearer while providing a smoothly contoured stoma surrounding opening to prevent irritation of the stoma upon intermittent contact therewith.

It will, of course, be understood that various changes may be made in the form, details, arrangement and proportions of the parts without departing from the scope of my invention which, generally stated, consists in the matter shown and described herein and set forth in the appended claims.

What I claim is:

1. A simplified stoma receiver comprising a highly pliable waterproof bag made from thin sheet material and having an inner layer adapted to be disposed in close association to the body of the wearer and an outer layer adapted to be disposed remotely of the body of the wearer, an annular mounting and retaining ring having an opening formed in the inner portion thereof to provide an inner periphery engaged with a portion of the outside surface of the inner bag layer and adapted to be disposed in close association to the body of a wearer, an annular clamping insert ring having an outer periphery constructed of a size and shape to be tightly pressed into the inner periphery of the mounting and retaining ring with the engaged portion of the bag disposed therebetween, said clamping insert ring being positioned inside of the bag in engagement with the inside surface of the inner bag layer and tightly clamped into the inner periphery of the outer mounting and retaining ring with the engaged bag layer tightly clamped therebetween, said clamping ring having a smoothly contoured inner periphery surrounding an opening therein, said inner bag layer being provided with an opening in substantial alignment with the opening of the insert ring to receive a stoma therethrough, and a pair of locking members pivotally mounted on the outer surface of said mounting and retaining ring and each of said locking members having a locking cam formed on one end thereof and an attachment element on the other end

thereof, said locking cams being shiftable into inwardly extending position in underlying relation to the outer peripheral portion of the surface of said insert ring disposed toward the inside of the bag and said attachment elements being disposed in outwardly disposed attaching position when said locking cams are in locking position.

2. A simplified stoma receiver comprising a highly pliable, at least slightly resilient, waterproof bag made from thin sheet material and having an inner layer adapted to be disposed in close association to the body of the wearer and an outer layer adapted to be disposed remotely of the body of the wearer and being provided with a closure at the upper and lower ends thereof and having a receiving aperture formed in the upper portion of said inner layer in spaced relation below the top thereof, an annular insert ring disposed on the inside of the bag, the outer periphery thereof engaging a portion of the inside surface of the inner layer of bag material surrounding said aperture and having a smoothly contoured inner periphery disposed in substantial alignment with the opening in said bag, a mounting and retaining member having an opening therein of a size and shape to receive in tightly clamped relation said insert ring therein to securely clamp said two rings together with the engaged bag portion interposed therebetween, shiftable means for securely locking said ring and retaining member in interfitting clamped relation, and means connected with the mounting and retaining member for permitting the same to be attached to the body of a wearer.

3. A simplified stoma receiver comprising a bag having a receiving opening formed through one side wall thereof, a mounting and retaining member having an opening therein substantially larger than the opening in said bag and surrounding said bag opening on the outside of the bag, an annular insert member positioned within the bag and having a stoma receiving opening therein and an outer peripheral shape and size to be tightly clamped into the opening in said mounting and retaining member, said two members being tightly clamped together with the portion of the bag surrounding the opening interposed therebetween and the bag opening aligned with the opening of said insert member, shiftable means mounted on said mounting and retaining member for positively locking said two members in clamped position, and means mounted on said mounting and retaining member for attaching the stoma receiver to the body of a wearer.

4. The structure set forth in claim 3, and the outer periphery of the insert member and the inner periphery of the mounting and retaining member being cooperatively grooved to provide a pair of opposed clamping shoulders cooperatively interfitting with one another when said two members are in clamped position with the engaged portion of the bag tightly clamped therebetween.
